UNITED STATES PATENT OFFICE.

JOSEPH EMEAKER, OF HAMILTON, OHIO, ASSIGNOR OF ONE-THIRD TO GEORGE MITCHELL
AND ONE-THIRD TO MIKE F. FRITTERER, OF HAMILTON, OHIO.

WINDOW.

No. 883,130.

Specification of Letters Patent. Patented March 24, 1908.

Application filed July 11, 1906. Serial No. 325,691.

To all whom it may concern:

Be it known that I, JOSEPH EMEAKER, citizen of the United States, residing at Hamilton, in the county of Butler and State of Ohio, have invented certain new and useful Improvements in Window-Sashes, of which the following is a specification.

This invention relates to window sashes and means for balancing the same; and it has for one of its objects to provide a sash embodying side sections and a glass-carrying section detachably connected to the side sections, whereby it may be readily removed to facilitate cleaning of the glass and may be as 15 readily replaced and secured to the side sections so as to move therewith.

Another object of the invention is the provision of a sash comprising side sections, a glass-carrying section arranged between and 20 detachably connected to the side sections, and weather - excluding and anti - rattling packing carried by the side sections and interposed between the same and the glass-carrying section.

Another object is the provision of simple and durable means coöperating with the side sections of the sash and adapted to efficiently 25 balance the sash so as to permit of the same being moved up and down with the expenditure of but a minimum amount of effort.

To the attainment of the foregoing objects, the invention consists in the peculiar construction, novel combinations and adaptation of parts hereinafter described and particularly pointed out in the claims appended.

In the accompanying drawings which are made a part hereof: Figure 1 is a front elevation of a sash frame and sashes constructed in accordance with my invention. Fig. 2 is 40 a detail view, partly in elevation and partly in vertical section, of my improvements.

Fig. 3 is an enlarged detail, horizontal section taken in a plane above the meeting rails of the sashes, looking downward. Fig. 45 4 is a broken perspective view of one side section of one sash, removed. Fig. 5 is a broken perspective view of the portion of the glass-carrying section which coöperates with the said side section. Fig. 6 is a perspective 50 view of one of the rack plates, removed. Fig. 7 is a vertical section of the same.

Similar letters and numerals designate cor-

responding parts in all of the views of the drawings, referring to which:

A is a sash frame constructed according to 55 my invention. The said frame is peculiar in that each of its side stiles *a* has parallel, vertical guide ways *b*, of dovetail form in cross-section, on its wall *c* adjacent to the sash, and vertically elongated openings *d* in said 60 wall, and also has vertical guide ways *e* back of the wall *c* for a purpose presently set forth.

B B are vertically movable weight bars arranged in the guide ways *e* of the frame stiles and having racks *f* on their sides adjacent to 65 the stile walls *c*.

C C are toothed wheels or spur gears mounted in the openings *d* of the stile walls *c* and intermeshed with the racks *f* of the weight bars B, and D D are the side sections 70 of the sash, which side sections are of dovetail form in cross section to snugly occupy the guide ways *b* on the stile walls *c* and are movable vertically in said guide ways. The said side sections D of the sash are provided 75 on their sides adjacent to the stile walls *c* with rack plates E, and these rack plates are intermeshed with the toothed wheels or spur gears C, whereby it will be seen that the weight bars B balance the sash so that the 80 latter may be moved up and down in the frame with the expenditure of but very little effort. In this connection it will be noticed that when either sash is raised its complementary weight bars B are moved downwardly, and when the sash is lowered its weight bars are raised, and this will be appreciated as an important advantage since it assures proper balancing of the sashes without the employment of the usual pulleys, cords and weights generally resorted to 85 for the purpose.

In their inner sides the side sections D of the sashes are provided with vertical grooves *m*, and in these grooves are arranged and 90 suitably secured packing strips F, preferably rubber tubes as shown, which have for their office to obviate rattling and to prevent the passage of air between the side sections D and the removable glass-carrying 100 sections presently described of the sash. Each rack plate E is formed of a thin body slotted to form the rack teeth and secured, one to the outer edge of each section D.

Said plates are each provided with an integral pin G at its lower end and an upper enlarged portion extending over and forming a continuation of the upper end of the section 5 D to which it is secured, said enlargement carrying a pivoted fastening member H. The pins G extend inwardly through their respective sections D and packing strips F, the fastening member H being hinged to the 10 upper end of the section so as to swing vertically, and being provided with a depending projection n, a slot p, and a finger portion r.

I I are the glass-carrying sections of the 15 sashes. These sections I are rectangular in form and are provided in the outer sides of their vertical bars with shallow grooves s designed to receive the packing strips F on the side sections D. The said sections I are also 20 provided in their lower corners with notches J designed to receive the pins G on the side sections D, and at their upper corners they are equipped with angle plates K, slotted at L to receive the projections n of the fastening 25 members H, and bearing turn-buttons M which are designed to pass through the slots p of said fastening members H and be turned into engagement therewith.

From the foregoing it will be apparent 30 that when the pins G on the side sections D are arranged in the notches J of the glass-carrying sections I, and the fastening members H of the side sections D are swung down against and fastened to the glass-carrying 35 sections I, each glass-carrying section will be fixed to its complementary pair of side sections so as to move up and down with said side sections as one piece. It will also be apparent that when the fastening members H 40 are released from the glass-carrying sections and are swung upward on their respective hinge-pintles into a vertical position, the glass-carrying sections can be swung on the pins G into a horizontal or approximately 45 horizontal position, this in order that the outer sides of the glass may be thoroughly cleaned with ease and despatch. It will also be understood that when released from the fastening members H, the glass-carrying sections I of the sash may be quickly and easily 50 removed entirely from the side sections D, as is desirable in case of fire or the like.

To replace and fasten the glass-carrying sections I of the sash in their respective side 55 sections D, it is simply necessary to arrange the notches J of sections I on the pins G and swing said sections I upward to positions between and in vertical alignment with their respective side sections D, and then swing 60 the fastening members H down into engagement with the glass-carrying sections and connect said members H to the glass-carrying sections through the medium of the turn-buttons M. In thus replacing the glass-car-

rying sections I, that of the upper sash is 65 first replaced, and then that of the lower sash. At this point it will be noted that in removing the glass-carrying sections I the order mentioned is reversed—i. e., the section I of the lower sash is removed before the 70 section I of the upper sash. From this latter it follows that when both sashes are lowered, the section I of the lower sash may be swung down and into an apartment from between its respective side sections D, and then 75 the section I of the upper sash may be swung down and into the apartment from between its respective side sections, and laid upon the first mentioned section I.

It will be gathered from the foregoing that 80 in addition to the practical advantages ascribed to my novel sash frame and sashes, the same are simple, compact and inexpensive in construction, and are well adapted to withstand the usage to which such devices 85 are ordinarily subjected.

The construction shown and described in detail constitutes the present and preferred embodiment of my invention, but it is obvious that in practice such changes or modifications may be made as fairly fall within the scope of my invention as claimed.

Having described my invention, what I claim and desire to secure by Letters Patent, is:

1. A window sash comprising side sections, an interposed glass carrying section, rack plates secured to the outer face of each side section and each provided with an integral pin extended through its respective 100 side section and detachably engaging the glass carrying section, and means carried by the upper ends of said rack plates for engaging said glass carrying section.

2. A window sash comprising side sections, an interposed glass carrying section, rack plates secured to the outer face of each side section and each provided with an integral pin extended through its respective side section and detachably engaging the glass carrying section, the upper end of each rack-plate being enlarged and extended over the end of its respective side section, and means carried by said enlarged portions for engaging the top of the glass carrying section.

3. A window sash comprising side sections, an interposed glass carrying section, rack plates secured to the outer edges of said side sections and each provided with an enlargement overlapping the top of its respective side section, a pivoted locking member mounted on the enlargement of each rack plate and adapted to engage the top of said glass carrying section, and means carried by said side sections for engaging the bottom of 125 said glass carrying section.

4. A window sash comprising side sections provided with grooved seats, an inter-

posed glass carrying section, packing strips located in the grooves of said side sections, rack plates secured to the outer faces of said side sections and each provided with an enlargement overlapping the top of its respective side section, the lower end of each rack plate being provided with an integral pin extended through its respective side section and packing, whereby said packing is secured 5 in position, said pins being adapted to engage

the bottom of the glass carrying section, and means carried by the enlarged portions of said rack plates for engaging the top of the glass carrying section.

In testimony whereof I affix my signature 15 in presence of two witnesses.

JOSEPH EMEAKER.
